[57] CLAIM

The ornamental design for an equine limb bandage, as
shown and described.

DESCRIPTION

FIG. 1 is a top plan view of an equine limb bandage,
showing my new design;

FIG. 2 is a bottom plan view thereof;

FIG. 3 is a front elevational view thereof;

FIG. 4 is a rear elevational view thereof;

FIG. 5 is a left side elevational view thereof; and,

FIG. 6 is a right side elevational view thereof.

FIG. 6
